UNDERWATER FOUNDATION AND METHOD
OF ERECTING THE SAMEMarney B. Willey, New Orleans, La., assignor to
J. Ray McDermott & Co., Inc., Houston, Tex.,
a corporation of Delaware

Application September 30, 1946, Serial No. 700,296

6 Claims. (Cl. 61—46)

1

This invention relates to new and useful improvements in underwater foundations and methods of erecting the same.

Heretofore, underwater foundations for oil well drilling rigs and the like have consisted of piling in the form of wooden timbers or metallic pipes. This piling has been reinforced by braces only above the surface of the water, thereby leaving the underwater portion of said piling unbraced and subject to the action of waves. It is extremely difficult and expensive to drive piling in the desired position and relation to other piling and very often the roughness of the water prevents the driving of piling for prolonged periods of time. Although piling has been driven and used in relatively shallow water, approximately sixteen feet in depth, it has been considered unsafe to use unbraced piling in water of greater depth, especially when the water is fifty to seventy feet deep, and it has been virtually impossible to brace the piling beneath the surface of the water. Due to the great length of unbraced piling, the same is flexible and subject to whipping or bending. This condition is accentuated in ocean locations having rough water, such as immediately offshore, and during storm seasons.

Therefore, one object of the invention is to provide improved foundation means of such construction as to be adaptable for underwater use in conjunction with piling for positioning and maintaining the piling in predetermined relation to one another.

A very important object of the invention is to provide an improved marine foundation for use in drilling and producing wells as well as other uses, the foundation including a prefabricated framework having hollow columns interconnected by transverse, reinforcing braces, being adapted to be constructed on shore and transported to the desired location for lowering into position upon the bottom of a body of water with the columns upright for the reception of piling adapted to be forced therethrough and anchored in supporting engagement with said bottom, whereby the time and cost of erecting the foundation is reduced to a minimum and whereby said foundation may be salvaged after use with a minimum amount of destruction.

Another object of the invention is to provide an improved underwater foundation having means making possible the accurate placement and alinement of piling and being reinforced so as to permit the use of the foundation in deep water.

2

A further object of the invention is to provide an improved underwater foundation having substantially upright means for receiving piling to be driven and reinforcing means connecting the piling receiving means, whereby said piling may be driven and maintained in position under adverse weather conditions in deep water and whereby the unsupported or unbraced length of said piling is reduced to a minimum.

Still another object of the invention is to provide an underwater foundation, of the character described, having bearing means adjacent its lower end for resting upon the ocean bed and thereby provide a firm footing for the foundation.

Still further object of the invention is to provide an underwater foundation, of the character described, which is adapted to form a substantially unitary structure with the piling received and maintained in position by the same; the foundation being initially fixed against movement by certain of said piling so as to permit the use of novel hammer means in driving the remainder of said piling.

A particular object of the invention is to provide an improved method of erecting underwater foundations wherein a reinforced foundation member is preconstructed and placed in position upon the ocean bed for the reception of piling, the latter being driven through the foundation member and maintained in position by said member whereby a unitary structure is had.

An important object of the invention is to provide an improved method of erecting underwater foundations wherein the desired spacing and alining of piling is obtained by means of a preconstructed foundation member resting upon the floor of the ocean, the foundation member reinforcing the piling so as to provide a rigid structure capable of withstanding adverse weather in deep water many miles from land.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a side elevational view of a plurality of underwater foundations, constructed in accordance with the invention, and shown as forming a base for an oil well drilling rig,

Fig. 2 is a side elevational view, taken at a right

angle to Fig. 1, of one of the foundation members,

Fig. 3 is an enlarged, horizontal, cross-sectional view, taken on the line 3—3 of Fig. 2,

Fig. 4 is a side elevational view of a portion of a foundation member embedded in the ocean floor with shoes resting upon the floor above the reinforced lower portion of said member,

Fig. 5 is an enlarged, detailed view, showing the relation of a pile to one of the receiving and supporting pipes of the foundation member,

Fig. 6 is a side elevational view of a pile-driving hammer, and

Fig. 7 is an enlarged, detailed view, illustrating the method of attaching a pile to its receiving and supporting pipe.

In the drawings, the letter A designates the mean level or surface of a body of water, such as an ocean, having a depth of fifty to seventy feet and a relatively flat bed or floor B. Underwater foundation members or frames 10, 11 and 12 rest upon the bed B and preferably project above the water level A for reinforcing piling 13 which is driven into said bed, as will be herein-after more fully explained. The upper ends of the piling 13 are connected by suitable cross-braces 14 and have platforms 15 mounted thereon for supporting an oil well drilling rig 16, or similar structure. It is pointed out that the quantity and size of the foundation frames vary in accordance with the use of the platforms 15 and the weight imposed thereupon. In addition to a derrick 17, the drilling rig 16 includes a drawworks 18, engines 19, a pipe rack 20, suitable tanks 21 and 22, and other equipment (not shown). Substructures 23 and 24 support the derrick 17 and engines 19, respectively, while the drawworks 18 is mounted upon both substructures, thereby permitting movement of said derrick, engines and drawworks for the purpose of off-set or directional drilling operations. As shown in Fig. 3, the foundation frame 10 has an enlarged, unobstructed medial space or opening 25 for accommodating a plurality of well connections (not shown).

Although the size, shape and construction of the foundation frames are subject to variation, the same are similar and are so shaped that when viewed from above they outline a geometrical figure of closed perimeter, preferably a rectangle or a square. A plurality of substantially upright, hollow, cylindrical members or pipes 26 of large diameter extend preferably throughout the length of each frame in spaced rows. Certain of the outermost of the pipes 26 have an outward and downward inclination or batter and the remainder of said pipes are substantially vertical (Figs. 2 and 3). It is essential to connect and reinforce the pipes substantially throughout their lengths by means of suitable cross-braces 27, which may be in the form of tubular rods or small pipes (Fig. 5). A pair of spaced, parallel shoes or bearing members 28 are suitably secured to the lower end of the pipes 26 and are disposed horizontally for engaging the ocean bed or floor B. The shoes 28 are preferably rectangular and extend transversely of the frame at opposite margins thereof, being formed of any suitable material, such as metallic plates or wooden planks.

It is pointed out that this position of the shoes is desirable when the ocean bed is relatively firm. However, when the bed is soft, such as in the case of a mud or silt bottom, it is preferable to position the shoes or bearing members above the lower end of the frame. A frame 29, similar to

the frame 10, is shown in Fig. 5 and includes similar pipes 30 which are reinforced by two sets of cross-braces 31 and 32 adjacent their upper and lower ends. Shoes or bearing members 33, similar to the shoes 28, are carried by the intermediate portion of the pipes 30 for resting upon the bed or floor, whereby the lower portions of said pipes and their cross-braces 32 are embedded in the mud or silt of said bed. Although not illustrated, the frame 29 is preferably of greater length than the frame 10 so as to permit the upper ends of the pipes 29 to project above the water level A when the lower ends of said pipes are embedded in the mud or silt bottom.

As is most clearly shown in Fig. 5, each pile 13 is preferably formed of pipe of less diameter than the pipe 26 whereby an annular space 26' is provided therebetween upon said pile 13 engaging within said pipe 26. It is pointed out that the piling 13 is of considerable length so as to have their upper ends projecting above the upper end of the frame 10 while their lower ends extend into the ocean bed an extent sufficient to engage a relatively firm earth formation. This penetration of the piling will be in the neighborhood of sixty to one hundred feet with the result that it will be necessary to form each pile of several sections which are preferably welded together. After driving the piling, the upper ends thereof are reinforced by the cross braces 14 and the platforms 15 and other structures, such as the derrick 17, are supported thereupon. In order to prevent movement of the piling relative to the pipes of the frame, it is desirable to fill each annular space 26' with sand or other suitable material (Fig. 5).

Due to the provision of the foundation frame for reinforcing the piling, said piling may be driven without the necessity of employing the usual pile driver which is mounted upon a barge and which cannot be used successfully under adverse weather conditions, such as rough water. Since the pipes 26 serve as guides for the piling, novel pile driving means may be used and the usual guides therefor may be eliminated. As shown in Fig. 6, the pile driving means may be in the form of a double-acting steam hammer 34 which is suspended from a boom (not shown) by means of a suitable cable or load line 35. An annular guide or skirt 36 depends from the lower end of the hammer 34 for engaging upon the upper end of a pile so as to support said hammer thereupon. If desired, the skirt 36 may be formed of a plurality of longitudinal elements or bars 37, having their intermediate portions connected as shown at 38, with their lower ends being bevelled as shown at 39 to facilitate engaging of said skirt upon the piling. The hammer 34 includes a suitable plunger or ram (not shown) which is adapted to be reciprocated by steam pressure for driving the piling. Manifestly, this arrangement permits the hammer to be maintained in alignment and supported by a pile during driving of the same without being dependent upon the load line 35 for its support.

In carrying out the improved method of erecting underwater foundations, the foundation frames 10, 11 and 12, all of lattice formation as above set forth, are constructed on shore and transported by barges to the desired location. Each frame is then lowered into position with its shoes 28 resting upon the ocean bed and its length is such that the upper ends of the pipes 26 project above the water level A. The piling 13 is next engaged within the pipe and driven into

said ocean bed. It is desirable, especially under adverse weather conditions, to drive certain of the piling at spaced points and to secure the same to their respective pipes, by welding or other suitable means, as shown at 40 in Fig. 7. Of course, it is not always necessary to perform this step. The steam hammer 34 is used in driving the piling and is supported upon each pile during the driving of the same as shown in Fig. 5. After partial erection of the foundation, it is possible and frequently desirable to support the boom upon said erected portion so as to eliminate the necessity for a barge. This arrangement is particularly advantageous under adverse weather conditions. After driving the piling, the space 26' between each pile and its pipe is filled with sand or other suitable material. Then, the upper ends of the piling are reinforced by the cross braces 14 to provide a substantially unitary construction for receiving the platform 15 and the other structures. It is pointed out that when the ocean has a soft bed, such as mud or silt, the foundation frame 29 is preferably used in place of the frames 10, 11 and 12. As has been hereinbefore pointed out, the lower reinforced portion of the frame 29 is embedded in the ocean bed or floor with the shoes 33 resting upon said floor as shown in Fig. 4.

From the foregoing, it is believed to be manifest that novel underwater foundations and method of erecting the same have been provided. The foundations are adapted to be used primarily in deep water, in the neighborhood of fifty to seventy feet, but may be used successfully in relatively shallow water having a depth of only twenty feet. The foundation frames not only reinforce the driven piling but also guide said piling during the driving thereof and permit the use of a freely suspended steam hammer. Obviously, a rigid, more durable and safe construction is made possible and the erection of the foundation is simplified, thereby saving both time and expense.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A foundation structure comprising a pre-fabricated framework made up of hollow vertical columns, which are all disposed in locations outlining a geometrical figure with a closed perimeter, cross brace members affixed to said columns and rigidly connecting said columns together, said framework thus being lattice-shaped, the framework being supported by the bottom of a body of water, piles driven through said columns and encased thereby and penetrating said bottom at their lower ends, to anchor said structure in position, and a horizontal platform over said

piles and said framework, to support a load on said piles.

5 2. A foundation structure comprising a pre-fabricated framework made up of hollow vertical columns, which are all disposed in locations outlining a geometrical figure with a closed perimeter, cross brace members affixed to said columns and rigidly connecting said columns together, said framework thus being lattice-shaped, the framework being supported on the bottom of a body of water, piles driven through said columns and encased thereby and penetrating said bottom at their lower ends to anchor said structure in position and a horizontal platform over said piles and said framework, to support a load on said piles, the lower ends of said columns having horizontally extended members to engage said bottom.

10 3. The method of constructing a foundation structure consisting in assembling tubular columns, open at both ends, connecting said columns at points intermediate the ends thereof by means of braces to form a rigid lattice-shaped framework, lowering said framework upon the bottom of a body of water, with said columns in upright position on said bottom, inserting piles into said columns through the open tops and forcing said piles into said bottom, and constructing a platform over said piles and said columns for supporting a load on said piles.

15 4. The foundation structure according to claim 1, wherein said hollow columns also have means for rigidly engaging the piles therein.

20 5. The foundation structure according to claim 2, wherein said hollow columns have means for rigidly engaging the piles within said columns.

25 6. The method of constructing a foundation structure consisting in assembling tubular columns, open at both ends, connecting said columns at points intermediate the ends thereof by means of braces to form a rigid lattice-shaped framework, lowering said framework upon the bottom of a body of water, with said columns in upright position on said bottom, inserting piles into said columns through the open tops and forcing said piles into said bottoms, making said piles rigid in said columns, and constructing a platform over said piles and said columns for supporting a load on said piles.

MARNEY B. WILLEY.
